UNITED STATES PATENT OFFICE.

GUSTAV E. HOGLUND, OF CHICAGO, ILLINOIS, ASSIGNEE OF ONE-HALF TO WILLIAM N. SELIG, OF CHICAGO, ILLINOIS.

MECHANISM FOR ELECTRICALLY TRANSMITTING AND REPRODUCING IMAGES.

1,030,240.

Specification of Letters Patent. Patented June 18, 1912.

Application filed April 18, 1910. Serial No. 556,089.

To all whom it may concern:

Be it known that I, GUSTAV E. HOGLUND, a citizen of the United States, residing at Chicago, in the county of Cook and State 5 of Illinois, have invented certain new and useful Improvements in Mechanism for Electrically Transmitting and Reproducing Images, of which the following is a specification.

10 The present invention relates to that class of devices which employs mechanism for cutting up and dividing light rays emanating from an image and causing them to act upon a substance as a selenium cell which is 15 capable of changing its electrical resistance under light rays of different degrees of intensity, the effect on a current passing through such a substance being to convert the current from a steady and constant flow 20 to a series of vibrations, which will vary in strength according to the way the various light rays affect the electrical resistance of the selenium cell. These vibrations are sent over a line and act upon a luminous center 25 at the other end thereof, which may be in the form of a speaking-arc, and cause a fluctuation in the brilliancy of said arc, which will cause light rays to emanate therefrom, said rays being of varying intensity, ac- 30 cording to the strength of the current. These light rays will follow each other in the same order and be of comparatively the same intensity as the light rays emanating from the object; hence, when 35 the rays from the lamp are projected onto the retina of the eye in rapid succession, they will cause an image to be built up before the eye which will be composed of the varying light rays of the same strength and 40 in the same order as those emanating from the original image. This phenomenon is possible because of the existence of a substance known as a selenium cell, which possesses the faculty of varying its power of 45 electrical resistance under the influence of light rays of varying intensity, and which is capable of acting on an electric current passing therethrough, to convert it from a steady flow to a series of vibrations when the 50 cell is acted upon by light rays of different degrees of intensity, and because of the persistence of vision of the retina of the eye, which enables an impression of an image to appear to the observer for a length of time 55 after the image has in fact disappeared.

I am aware that this principle of operation has been disclosed in the patent to Sellers, No. 939,338, issued November 9, 1909; but I claim that there are certain mechanisms and principles of operation involved in my invention which are not disclosed in the Sellers patent above referred to, and these I claim as new and novel.

The objects of the present invention are, to construct a mechanism for accomplishing the above described result, which will be cheap and simple of construction, and which will not necessitate any involved electrical circuits or complicated mechanism; to arrange the mechanism whereby an image may be transmitted from each end of a line and reproduced at the other end; to use a lamp as a reproducing instrument, which will be acted upon directly by the current to cause a fluctuation in the intensity of light rays emanating therefrom, to build up the image before the eye; and to construct a peculiar form of shutter for cutting the rays emanating from the image to allow them to project successively on the selenium cell, and to cut up the rays emanating from the lamp to allow them to pass through the shutter in successive order.

The invention further consists in the features of construction and combination of parts hereinafter described and claimed.

While I have shown and contemplated one form of this invention, covering the arrangement whereby an image may be transmitted from either end of the line and reproduced at the other end, it is obvious that this is a mere duplication of the arrangement for transmitting an image from one end of the line to the other, and desire, therefore, to have it understood that the principle of operation and the parts for carrying out the same are equally applicable in either case, and that my invention is not necessarily limited to either specific form.

In the drawings, Figure 1 is a diagrammatic view, showing the mechanism and circuit for transmitting an image from one end of the line to the other; Fig. 2, a diagrammatic view, showing the mechanism and circuit for transmitting an image from each end of the line and reproducing it at the other, and also shows the mechanism used in conjunction with telephone receivers and transmitters; Fig. 3, a detail showing a front view of one form of shutter of the

present invention; Fig. 4, a rear view showing the shutters of Fig. 3 in one position; Fig. 5, a rear view showing the shutters of Fig. 3 in another position; Fig. 6, a sectional detail, showing gearing for operating the shutters of Fig. 3; Fig. 7, a detail showing a modified construction of shutter; Fig. 8, an enlarged detail, showing the mechanism at one end of the line for operating the shutter disclosed in Fig. 7; Fig. 9, an enlarged detail of the mechanism shown in Fig. 8; Figs. 10 and 11, fragmentary views showing the form of shutter disclosed in Fig. 7 in two different positions; and Fig. 12, a diagrammatic view, showing the lines marked across the surface of an image by the movements of the shutter shown in Figs. 3, 4 and 5.

Referring to Fig. 1, located at one end of a line is a mechanism 13, which may be termed the transmitting mechanism, and at the other end of the line is mechanism 14, which may be termed the receiving mechanism. The transmitting mechanism comprises a reducing lens 15 and an enlarging lens 16, interposed between which is a shutter 17; and positioned in the focus of the enlarging lenses is a selenium cell 18. There are other equivalents for the selenium cell known to science. It is, therefore, understood that I use the term "selenium" merely for brevity in description, as, obviously, any of the other substances known to science would serve the purpose equally as well, and I do not desire to limit my invention to this particular substance.

The receiving mechanism 14 comprises a lamp 19, preferably of the type known as the speaking-arc, and further comprises enlarging lenses 20, between which may be interposed, if desired, a ground glass plate 21, upon which the reproduction of the image may be viewed, or from which it may be projected onto a suitable screen; and interposed between the lenses 20 and the lamp 19 is a shutter 22. The shutter 17 and the shutter 22 are alike in form and operation; therefore, a description of one of the shutters will answer for both of them.

The form of the shutter 22, shown in Figs. 3, 4 and 5, comprises an outer disk 23 and an inner disk 24. The outer disk 23, as shown, has formed therein a plurality of slots or openings 25, of equal length and width, which extend in a stepped line outward from the center of the disk and are arranged in stepped formation from the outer edge of the disk toward the center. The disk 24 comprises, as shown, a plurality of elongated arcuate slots 26, which extend parallel with the outer periphery of the disk and are arranged in spiral stepped formation from the outer edge toward the center of the disk and are all of equal width.

When the disks are placed in operative position adjacent to one another as shown

in Fig. 1, there will be one of the openings 25 lying equidistant from the center of the disks with one of the openings 26; that is to say, the outer opening of the slots 25 is equidistant from the center of the disk with the opening 26 lying nearest to the outer periphery of the disk 24 and the next opening 25 is equidistant from the center of the disk with the second opening 26. This arrangement is maintained throughout the entire series of openings.

The disks in use are rotated in opposite directions and at varying speeds with one another. The ratio of speed between the outer disk and the inner disk is as the number of openings is to one. That is to say, if there are five openings in the disks, as shown in the drawings, the disk 23 will make five revolutions to each revolution of the disk 24. The effect of this will be that while the disk 24 is revolving once past the field of vision of the object, the disk 23 will have made five revolutions, so that each of the openings 25 will have been brought into register with each of the openings 26 while the latter opening is traversing the field of vision. As both of the shutters are moved at the same time, it is, of course, necessary that the slots 26 be of a somewhat greater length than the length of the field of vision; otherwise the slots 26 would pass across the field before the openings 25 had entirely passed across, so that the light rays from some portion of the object would not be admitted through the opening produced by the registering of the openings 25 with the openings 26.

By referring to Fig. 12, the method of cutting up the image will be clearly seen. Each of the curved lines 26^a in this figure represents the path of travel of one of the slots 26; and the spaces between the vertical lines 26^b represent the different positions assumed by the openings 25 during their travel across the openings 26. That is to say, upon the initial movement of the shutter, the outer slot of the series of slots 26 will assume the position indicated by the first two upper curved lines 26^c, shown in Fig. 12; and when the disk 23 moves so that the outer opening 25 is brought into register with the outer opening 26, the reflection from the image will be cut across transversely of the curved lines, thus cutting the light rays emanating from the upper edge of the image into a series of rays which will successively be allowed to project through the openings 25 and 26 and onto the selenium cell. This operation will be repeated by the various openings until the entire image has been traversed and the reflections from the image cut up and allowed to project successively on the selenium cell. As will be seen from the drawings, the openings are so arranged that it is impossible for more than 130

one opening in each set of openings to be in register at a single time within the field of vision.

In Figs. 7 to 11, I have shown a modified construction of shutter, which is formed of inner and outer disks 27, each having therein a plurality of elongated openings 28, which openings are lying at an angle with regard to the radial lines of the disk. In this construction, the field of vision is narrowed by proper lenses until it assumes an elongated shape similar to one of the openings; and the disks are revolved in opposite directions from one another and at the same speed, so that when the slots 28 in the disks come into register with one another, they will pass by and produce a small opening 29, through which the light rays will filter. By referring to Figs. 8, 10 and 11, where three different positions of the shutter are shown, this principle of operation will be clearly understood.

Referring to Fig. 1, the selenium cell 18 and the lamp 19 are connected by an electrical circuit 29, and the current to the lamp is preferably strengthened by means of a local circuit 30 acting in conjunction with an induction coil 31. The shutters 22 and 17 are each actuated by motors 32, operated from a suitable source of power 33. The motors 32 may be of any suitable and well known type of that class of motors known as synchronous. The motors 32 are attached to a driving shaft 34, which extends through a housing 35, which, as shown, is part of the shutters 23 and 24. Inclosed within the housing is suitable gearing 36, driven by the shaft 34, and of a ratio to impart the proper relative speed to the disks 23 and 24.

The operation of the device shown in Fig. 1 is as follows: The motors 32 are started, operating the shutters 17 and 22, and when the motors are regulated so as to run in synchrony with one another, the shutters 17 and 22 will be revolving synchronously, so that as the light rays emanating from the object to be transmitted are projected onto the selenium cell, the shutter 22 will be in a position to permit the rays emanating from the lamp 19 to pass out through the shutter in the same order that they are passing in through the shutter 17. That is to say, when the upper slots 25 and 26 of the disks comprising the shutter 17 are in register with one another, and are operating to allow the light rays from the upper portion of the image to strike upon the selenium cell, the upper slots 25 and 26 in the disks comprising the shutter 22 will be in register to allow the rays to pass out therethrough from the lamp 19, so that when the two shutters are working in synchrony, light rays will be passing through the shutter 22 from the lamp 19, which will be in the same

order and of the same strength as the rays from the image passing through the shutter 17. And, as heretofore stated, owing to the persistence of vision of the retina of the eye, the rays from the lamp 19 will pass out in such rapid succession that the eye will retain them sufficiently long to build up an image therefrom; and as the rays are of the same strength and come in the same order as the rays emanating from the image, the image built up at the receiving station will be in form and shade effects the same as the image at the transmitting station. Thus it will be possible to reproduce scenes from life or images at a point distant from where they are located or occurring.

The device shown in Fig. 2 comprises a transmitting instrument 37 and a receiving instrument 38, which are arranged in sets so that the mechanism at each end of the line 35 comprises a transmitting and a receiving instrument. Each of the transmitting instruments comprises a selenium cell 39, positioned in front of which is an enlarging lens 40 and a reducing lens 41; and between the lenses 40 and 41 is a shutter 42 similar to the shutters 17 and 22. Each of the receiving instruments comprises a lamp 43 and enlarging lenses 44, between which is positioned, if desired, a ground glass 45; and the receiving 95 and transmitting instruments are connected by a suitable electrical circuit 46, the shutters being revolved by synchronous motors 47, actuated from a suitable source of power 48. This device is adapted and can be used, 100 if desired, in connection with a telephone system, so that in talking by telephone, the speaker is enabled to observe the person with whom he is talking. In this form of device I contemplate the use of a single shutter for 105 the transmitting and receiving instrument at each end of the line. And, as shown in Fig. 2, the shutters are revolving so that when rays are passing from the image onto the selenium cell at one end of the line, they are 110 passing out from the lamp at the other end of the line, hence, a continual series of vibrations is passing through the electrical connection between the two stations, conveying the vibrations from the transmitting instrument at each of the stations to the receiving instrument at each of the stations, and this will be possible without any interference of the current, because current will only be flowing in one direction at the same time, due to the fact that but one receiving instrument and one transmitting instrument at either end of the line will be operating at the same time.

It is, of course, necessary, in order to get the proper results in instruments of this character, that the two shutters be brought into proper relation to one another. It can be easily determined when such relation is found by observing the image coming from

- the receiving instruments. If the shutters are not in proper relation, the image will be nothing more than a blur, and before it can be distinctly seen, the shutters will have to 5 be in proper relation to bring the openings into the desired position. I, therefore, provide handles 48, which extend out from the shutters, and by turning these handles, the shutters can be revolved until they are 10 brought into proper relation with one another, the operator determining when such position has been reached by observing the completeness of the image reproduced by the receiving instrument. After the shutters have been operated so as to be brought 15 into proper relation with one another, the motors will then operate them in synchrony, so that no further manipulations are necessary.
- 20 The operation of the device shown in Fig. 2 briefly is as follows: The shutters are first brought into proper relation with one another. Then, when such relation is effected, light rays will be emanating from the lamp 25 at the receiving station in the same order and of the same strength as those at the transmitting station at the opposite end of the line, so that the reproduction of an image at one end of the line is constantly 30 made at the other end of the line, the principle of operation being the same as that of the device shown in Fig. 1.
- In order to obtain a complete picture the 35 mechanism can be so adapted as to obtain a plurality of exposures of the same image.
- I claim:
1. In a device of the class described, the combination of a transmitting instrument and a receiving instrument, the transmitting 40 instrument comprising a selenium cell and a shutter, the receiving instrument comprising a luminous center and a shutter, means for operating the shutters in synchrony with one another, each of the shutters comprising 45 companion disks lying adjacent to one another and rotated in opposite directions, one of the disks being provided with arcuate slots, and the other disk being provided with a plurality of slots extending in a stepped line outwardly from the center of the disk, adapted to register successively with the arcuate slots, and an electrical connection 50 between the selenium cell and the luminous center, substantially as described.
  - 55 2. In a device of the class described, the combination of transmitting instruments, each comprising a selenium cell and a shutter, receiving instruments, each comprising a luminous center and a shutter, means for operating the shutters in synchrony with one another, each of the shutters comprising 60 companion disks adjacent to one another and rotated in opposite directions, one of the disks being provided with arcuate slots, and the other disk being provided with a 65

plurality of slots extending in a stepped line outwardly from the center of the disk and adapted to register successively with the arcuate slots, one of said transmitting instruments and one of said receiving instruments being located at each end of the line, and an electrical connection between the receiving instruments and transmitting instruments at opposite terminals of the line, substantially as described. 70

3. In a device of the class described, the combination of a transmitting instrument and a receiving instrument, the transmitting instrument comprising a selenium cell and a shutter, the receiving instrument comprising a luminous center and a shutter, means for operating the shutters in synchrony with one another, each of the shutters being in the form of disks lying adjacent to one another and rotated in opposite directions, one of the 80 shutters being provided with arcuate slots of equal width and arranged in spiral stepped relation, and the other disk being provided with a plurality of slots extending in a stepped line outwardly from the center of the disk and adapted to register successively with the arcuate slots, and an electrical connection between the selenium cell and the luminous center, substantially as described. 85

4. In a device of the class described, the combination of transmitting instruments, each comprising a selenium cell and a shutter, receiving instruments, each comprising a luminous center and a shutter, means for operating the shutters in synchrony with one another, each of the shutters being in the form of disks lying adjacent to one another and rotated in opposite directions, one of the disks being provided with arcuate 90 slots of equal width and arranged in spiral stepped relation, and the other disk being provided with a plurality of slots extending in a stepped line outwardly from the center of the disk and adapted to register successively with the arcuate slots, one of said transmitting instruments and one of said receiving instruments being located at each end of the line, and an electrical connection between the receiving instruments and transmitting instruments at opposite terminals of the line, substantially as described. 95

5. In a device of the class described, the combination of a transmitting instrument and a receiving instrument, the transmitting instrument comprising a selenium cell and a shutter, the receiving instrument comprising a luminous center and a shutter, means for operating the shutters in synchrony with one another, each of the shutters being in the form of disks lying adjacent to one another and rotated in opposite directions, one of the disks being provided with arcuate slots of equal width and arranged in spiral stepped relation, and the other disk 100

being provided with a plurality of slots extending in a stepped line outwardly from the center of the disk, mechanism operatively connected to the disks for revolving them at different speeds, the ratio of speed of the disk having the stepped slots to the speed of the disk having the arcuate slots being as the number of slots is to one, and an electrical connection between the selenium cell and the luminous center, substantially as described.

6. In a device of the class described, the combination of a transmitting instrument and a receiving instrument, the transmitting instrument comprising a selenium cell and a shutter, the receiving instrument comprising a luminous center and a shutter, means for operating the shutters in synchrony with one another, each shutter comprising companion disks lying adjacent to one another and rotated in opposite direction, and the other disk having a plurality of arcuate elongated slots extending parallel with the circumference of the disk, each of the slots being equal in width and arranged in a spiral stepped formation from the outer edge toward the center of the disk, and the other disk having a plurality of slots of smaller area than the arcuate slots and extending in a stepped line outwardly from the center of the disk and adapted to register with the arcuate slots, mechanism operatively connected for rotating the two shutters, whereby the shutter having the stepped slots will make a complete revolution, while the shutter having the arcuate slots is moving a distance sufficient to move one of the arcuate slots past the field of vision, and an electrical connection between the selenium cell and the luminous center, substantially as described.

7. In a device of the class described, the combination of transmitting instruments, each comprising a selenium cell and a shutter, receiving instruments, each comprising a luminous center and a shutter, means for operating the shutters in synchrony with one another, each shutter comprising companion disks lying adjacent to one another and rotated in opposite directions, one of the disks having a plurality of arcuate elongated slots extending parallel with the circumference of the disk, each of the slots being equal in width and arranged in a spiral stepped formation from the outer edge toward the center of the disk, and the other disk having a plurality of slots of smaller area than the arcuate slots and extending in a stepped line outwardly from the center of the disks and adapted to register

with the arcuate slots, mechanism operatively connected for rotating the two shutters, whereby the shutter having the stepped slots will make a complete revolution, while the shutter having the arcuate slots is moving a distance sufficient to move one of the arcuate slots past the field of vision, one of said transmitting instruments and one of said receiving instruments being located at each end of the line, and an electrical connection between the receiving instruments and transmitting instruments at opposite terminals of the line, substantially as described. 65

8. In a device of the class described, a shutter comprising companion disks lying adjacent to one another, mechanism operatively connected for rotating said disks in opposite directions at different rates of speed, one of said disks being provided with a plurality of relatively elongated arcuate 80 slots having their ends closely adjoining, said slots being spaced apart across the surface of the disk to form the elements of a practically continuous spirally extending slot from the edge toward the center of the 85 disk, and each slot extending parallel with the outer periphery of the disk, and the other disk being provided with a plurality of relatively contracted slots extending in a stepped line outwardly toward the circumference of the disk, each of the contracted slots being adapted to register with one of the arcuate slots when said slots are passing across a field of vision, the disk having the contracted slots rotating at a greater speed 95 than the disk having the elongated slots, the ratio of speed being as the number of slots is to one, substantially as described. 90

9. In a device of the class described, a shutter comprising companion disks lying adjacent to one another, mechanism operatively connected to said disks for rotating them in opposite directions, one of the disks being provided with a plurality of relatively elongated arcuate-shaped slots having their 100 ends closely adjoining, said slots being spaced apart to form a practically continuous spirally extending slot from the outer edge toward the center of the disk, the other disk being provided with a plurality of 105 relatively contracted slots extending in a stepped line outwardly toward the circumference of the disk, the two sets of slots being adapted to register one with the other, substantially as described. 110
